UNITED STATES PATENT OFFICE

HELENA L. GREENE, OF BROOKLINE, MASSACHUSETTS

CATAMENIAL BELT

Application filed February 5, 1929. Serial No. 337,585.

This invention relates to catamenial belts, and the principal object of the invention is to provide a belt of simple and inexpensive construction which may be readily applied 5 and adjusted about the wearer's waist, conveniently attached to the napkin, worn with comfort, and quickly removed for laundering or disposal. Further features of the article will be hereinafter described, and defined in 10 the appended claims.

A recommended embodiment of the invention is illustrated in the accompanying drawing which shows a perspective view of the improved belt prior to the attachment of 15 the napkin.

The belt is preferably formed of inexpensive and inelastic fabric tape or belting, and comprises a waist-encircling loop 1 having free ends 2 and 3 at the front, and a small 20 loop 4 surrounding the loop 1 at the rear and adapted to be slid lengthwise of said loop to proper adjusted position for use. The loop end 2 is doubled back at 5 and then folded diagonally at 6 and stitched at 7 with 25 the oblique rough edge of the strip disposed within the fold 6. The resulting three-ply portion has a small opening 8 through which the loop end 3 is inserted. The end 3 may be hemmed at its free edge 9 and is prefer- 30 ably formed with one or more stitched tucks 10 which provide spaced obstructions against free passage of the loop end 3 through the restricted opening 8.

In use the belt loop 1 is adjusted to proper 35 position about the waist by drawing the end 3 through opening 8, and the loop ends 2 and 3 are pinned together and to one end of a catamenial bandage or napkin, the other end of the bandage being pinned to the de- 40 pending portion of the movable loop 4. The belt may accordingly be comfortably fitted to waist lines of varying sizes; for the adjust- 45 ability of the loop 1 is limited only by the length of the tape, and proper adjustment is obtained without the use of special fastenings. The tucks 10 not only assist in effecting approximate adjustment until the 50 ends 2 and 3 are pinned together, but also tend to prevent accidental withdrawal of the end 3 through the opening 7 when the article

is not in use, and accordingly serve to retain the loop 4 upon loop 1 against possible separation or loss.

A belt constructed as above described may obviously be prepared at minimum cost from inexpensive materials and with few stitching operations. Hence, although it may be worn and laundered repeatedly without impairing its efficiency or adjustability, the entire article may be discarded after a single wearing 55 and substituted by a fresh belt at very slight expense. Owing to its cheapness the belt is peculiarly adapted to be packaged and sold together with one or more sanitary napkins, 60 in the convenient and well recognized manner in which such articles are now commercially merchandised. 65

I claim:

1. A catamenial belt comprising a flexible, 70 waist-encircling loop of inelastic material having its free ends depending from the front of the belt, the material being folded diagonally upon itself remote from one of said ends and secured in folded position, the folded portion having a relatively small aperture therethrough, the other end of the loop being threaded through said aperture so that the effective length of the loop may be adjusted by drawing said end away from the folded portion, and a small loop surrounding 75 the large loop and movable to a position at the rear of the belt, the depending free ends of the large loop being arranged to be pinned together and to one end of the bandage which has its opposite end pinned to the small 80 loop. 85

2. A catamenial belt comprising a flexible, 90 waist-encircling loop of inelastic material having its end portions depending from the front of the belt, one of said end portions being folded diagonally upon itself remote from its extremity and stitched in folded position, the folded portion having a relatively small aperture therethrough, the other end portion being threaded through said loop and constricted thereby, the effective length of the loop being adjustable by drawing said end portion through the aperture, and a small 95 closed loop surrounding the large loop and movable to a position at the rear of the belt, 100

the depending end portions of the large loop being arranged to be pinned together and to one end of the bandage which has its opposite end pinned to the small loop.

3. A catamenial belt comprising a flexible, waist-encircling loop of inelastic material having its end portions depending from the front of the belt, one of said end portions being folded diagonally upon itself remote from its extremity and stitched in folded position, the folded portion having a relatively small aperture therethrough, the other end portion being threaded through said loop and constricted thereby, the effective length of the loop being adjustable by drawing said end portion through the aperture, said end portion having a plurality of longitudinally spaced transverse tucks providing obstructions which impede the withdrawal of said end through said aperture and a small closed loop surrounding the large loop and movable to a position at the rear of the belt, the depending end portions of the large loop being arranged to be pinned together and to one end of a bandage which has its opposite end pinned to the small loop.

Signed by me at Boston, Massachusetts, this 1st day of February, 1929.

HELENA L. GREENE.
